TONGS FOR FOREHEARTH SKIMMER BLOCKS AND THE LIKE

Francis N. Dailey, Rockville, Conn., assignor to
Hartford-Empire Company, Hartford, Conn.,
a corporation of Delaware

Application September 11, 1947, Serial No. 773,338

2 Claims. (Cl. 294—112)

1

This invention relates to a device for use in removing and replacing refractory skimmer blocks of molten glass conducting forehearts or flow channels.

Molten glass forehearts customarily include a transversely extending refractory skimmer block which is supported, as on the side walls of the forehearth channel, so that the lower edge of the skimmer block is located at or just below the surface of the molten glass in the forehearth channel. Such a skimmer block may require removal and replacement while the forehearth is in operation either because the skimmer block has been worn by erosion of the glass or has broken or cracked in service or for other reasons. The skimmer block is located in a zone of high temperature and is too hot to be grasped and lifted by hand. Prior to the present invention, it has been customary to remove such a skimmer block by the use of pry bars and other available tools, manipulated by workmen. This not only is hazardous for the workmen but is a difficult and tedious operation. Even with care, the hot skimmer blocks or a part thereof if it should be cracked or broken, may fall or slip away from a supporting bar or other tool. Also, in setting a new skimmer block in place in the forehearth, it is necessary first to effect pre-heating of the block, as to a temperature of 800° or 900° F. before the skimmer block is placed in its operative position. Otherwise the new skimmer block is likely to be broken by heat shock when it is first exposed to the high temperature existing in the forehearth channel. Sometimes, in order to avoid handling a skimmer block preheated to such a high temperature, the skimmer block is propped on temporary supporting blocks above the location at which it is to be set and thereafter the supporting blocks are knocked out of their supporting positions gradually to lower the skimmer block toward and ultimately to its final position as it becomes preheated by heat from the forehearth.

A general object of the invention is to facilitate removal of a skimmer block from a forehearth channel and its replacement by a new skimmer block and to do this without requiring manual handling of the block or exposure of a workman to the hazards incident to the prior practice.

A more specific object of the invention is to provide a tongs by which a hot skimmer block can be firmly, although releasably, gripped and moved by a hoist or other mechanical device under the control of a workman, as for the re-

2

moval of a hot skimmer block from a forehearth channel or the positioning of a new preheated skimmer block in the forehearth channel.

A further object of the invention is to provide a tongs of the character described which will afford facilities for engaging a hot skimmer block so as to tend to maintain parts thereof against separation in the event the skimmer block is cracked.

10 A further object of the invention is to provide a tongs of the character described which is reliable in use, relatively simple construction and includes no clamping screws or threaded parts which are likely to be impaired or rendered inoperative by refractory dust or the heat to which the device will be subjected or to require adjustment by a wrench or the like in a hot or dangerous environment.

Other objects and advantages of the invention 20 hereinafter will be pointed out or will become obvious from the following description of a tongs embodying the present invention and a typical use thereof, such embodiment being shown in the accompanying drawings, in which:

25 Fig. 1 is a face view of a skimmer block with the tongs of the present invention engaged therewith at a time when the skimmer block has been lowered to its operative position in a molten glass forehearth channel which is shown in section, the view also showing in dot-and-dash lines the relative positions of the movable parts of the tongs after the latter has been operated to release the skimmer block and raised above it;

30 Fig. 2 is a relatively enlarged plan view of 35 the tongs engaged with the skimmer block as shown in full lines in Fig. 1, the forehearth being omitted; and

35 Fig. 3 is a section through the tongs substantially along the line 3—3 of Fig. 2, with the skimmer block omitted.

40 The novel tongs of the present invention comprises a rigid crossbar 1 made of steel or other suitable metal or material and of sufficient length to extend a short distance beyond each of the side edges of the upper part of a refractory skimmer block 2 when the crossbar is disposed above and parallel to the top of the skimmer block with the transverse median line of the crossbar approximately aligned with the vertical median line of the skimmer block. A pair of depending tong arms 3 are mounted by horizontal pivot pins 4 on the crossbar 1 at equal distances from the transverse median line of the crossbar such that these arms will hang vertical beside the 45 opposite side edges of a relatively wide upper

portion 2a of the skimmer block when the crossbar 1 is disposed above the skimmer block as above stated. The tong arms 3 are provided at their lower ends with rigid inturned block engaging elements or tong fingers 5 which are then located in positions to extend into lateral notches or recesses 6 in the side edges of the upper portion of the skimmer block, these notches preferably being provided in such skimmer block just above the downwardly facing shoulders 7 provided on the skimmer block because of the relatively less width of its narrower lower portion 2b. The narrower portion 2b of the skimmer block is adapted to fit between the side walls 8 of a refractory forehearth channel 9 to a level just below the surface of a stream of molten glass 10 in that forehearth channel when the downwardly facing shoulders 7 rest upon the upper edges of the sides 8 of the forehearth channel, as shown in Fig. 1.

The crossbar 1 is provided on its lower surface with presser blocks or pads 11 which respectively are located equi-distant from the transverse median line of the crossbar intermediate that transverse median line and the planes of the side edges of the upper part 2a of the skimmer block so as to bear downwardly on the upper surface of the skimmer block when the tong fingers 5 are engaged in the notches 6 in the side edges of the skimmer block. These blocks or pads 11 may be made of steel or any other suitable material which obviously may include a material that is sufficiently compressible to assure firm contact with the upper surface of the skimmer block without interfering with movement of the tong fingers 5 to their engaged positions in the notches 6 should the dimensions of the parts involved vary slightly from optimum or specified dimensions. As shown by Figs. 2 and 3, these blocks or pads 11 extend beyond opposite sides of the crossbar 1 so as to contact with the top surface of the skimmer block 2 throughout the greater part of its width.

The crossbar 1 also carries depending abutments or stops 12 in positions to be located close to but outwardly of the side edges of the upper corner portions of the skimmer block when the tong fingers 5 are engaged in the slots 6 of the skimmer block and the pads or blocks 11 bear against its upper surface, as shown in Fig. 1. These abutments or stops 12 may be short metal angles 13 welded or otherwise rigidly secured to the lower side of the crossbar 1 at appropriate places along the length of the latter, these angle pieces being of sufficient length to extend short distances beyond opposite sides of the crossbar 1 as is clear from Figs. 2 and 3. The purpose of the abutments or stops 12 is to limit relative longitudinal movements between the crossbar 1 and the skimmer block 2 when the tong fingers 5 are engaged in the notches 6 to only such movements as will not permit either tong finger to be accidentally disengaged from its notch.

The crossbar 1 is provided intermediate the pivot elements 4 with an upstanding rigid attaching lug or plate 14. This has a hole 15 provided therein near its upper end and intermediate its side edges, with which a hook 16 at the lower end of the chain 17 of a hoist (not shown) may be engaged. The hoist or any other suitable known mechanical lifting aid may of course be used to support and move the tongs for use of the latter as hereinafter will be described.

The tong arms 3 are provided with actuators

in the form of rigid arms 18 which may be formed integral with the tong arms so as to extend upwardly above the crossbar 1 in planes which are inclined inwardly or toward each other. The actuating arms 18 are operable by a second crossbar 19 with which they are connected for limited sliding and oscillatory or swivelling movements. As shown, the arms 18 are provided near their upper ends with blocks 20 rigid therewith, as by being welded thereto, these blocks being provided with aligned bores 21 which are oversize in relation to the transverse dimensions of the second crossbar 19. The latter may be a length of round metal pipe or rod and the diameter of the bore 21 in each of the blocks 20 is sufficiently greater than the diameter of the round pipe or rod to permit sufficient swivelling or oscillatory movements of the blocks 20 relative to the bar 19 to permit them to slide along the latter when the actuating arms are to be operated to swing the tong arms between closed and open positions as shown by full lines and dot-and-dash lines, respectively, in Fig. 1.

The crossbar 19 is of greater length than the crossbar 1 so that it has projecting end portions, indicated at 19a, which may be grasped by workmen when it is desired manually to carry or move the tongs.

A pair of guard elements in the form of collars 22 may be provided on the crossbar 19 at places adjacent to but equi-distant from its middle point.

In use to remove a skimmer block from the forehearth channel, the tongs may be lowered while the tong arms are open, as shown by the dot-and-dash lines in the upper part of Fig. 1, the hook of the hoist, if one is employed, then being engaged with the attaching lug or plate 14 on the crossbar 1. At this time, the crossbar 19 will bear against lower portions of the walls of the bores 21 in the blocks 20, at least at the outer ends of such bores, as shown by the dot-and-dash lines in Fig. 1 and the blocks 20 will be located at positions spaced inwardly from stop pins 23 on the crossbar 19, the tong arms 3 being in their outwardly swung positions. When the tongs have been moved until the crossbar 1 is positioned above the skimmer block 2 as shown by the full lines in Fig. 1, the hook of the hoist is disengaged from the attaching lug 14 and engaged with the portion of the crossbar 19 between the collars 22. Now, when a lift is applied to the crossbar 19, the blocks 20 will slide outward on such bar against the stop pins 23 and the tong fingers 5 will enter the notches 6 in the side edges of the skimmer block. A further upward pull on the crossbar 19 will lift the entire tongs mechanism with the tong fingers engaged in the notches 6 so as to lift the skimmer block from the forehearth channel. It will be observed that this skimmer block will then be compressed sufficiently between the tong fingers 5 with relation to one another and between these tong fingers and the pads or blocks 11 to maintain the skimmer block in compression and thereby to prevent separation of it into a number of parts should it be cracked. Also, such clamping of the skimmer block to the tongs will prevent undue stress on the tong fingers to resist overturning or tilting of the skimmer block in the tongs even though the center of gravity of the skimmer block be somewhat above the level of the tong fingers.

To release the tongs from the skimmer block, after the skimmer block has been removed and

lowered to a suitable supporting surface (not shown), it is only necessary to detach the hook of the hoist chain from the upper crossbar 19, as for subsequent attachment to the apertured lug or plate 14. The weight of the crossbar 19, bearing down on the blocks 20 and the inclined arms 18, will cause the tong arms 3 to swing apart as the blocks slide inwardly on the crossbar 19 from the positions shown by full lines in Fig. 1 to the positions shown by dot-and-dash lines in the same view.

To install a new skimmer block in the desired position in a forehearth, as shown in Fig. 1, the tong fingers may be engaged in the notches in the side edges of that skimmer block, which may be suitably preheated. The hook of the hoist chain may be engaged with the upper crossbar 19 for the installation and the skimmer block moved by the hoist and under the control of a workman to the desired position. The tong fingers then may be disengaged from the skimmer in a manner which has been explained. Thus, the workman can control the movements of the mechanism required for removal and replacement of a skimmer block while remaining at a safe distance from hot refractory parts and the hot forehearth environment.

The novel tongs of the invention is designed and intended for use to remove and replace hot skimmer blocks of molten glass conducting forehearts but is not limited thereto as it may be used to transport any other work piece or article which may be gripped and carried thereby. Nor do I wish to be limited to the details of the illustrative embodiment of the invention shown in the drawings and herein particularly described as many modifications of and changes therein will now be obvious or readily occur to those skilled in the art.

I claim:

1. A tongs, for a glass forehearth skimmer block or other workpiece, comprising a crossbar, a pair of tong arms pivotally suspended from the crossbar, workpiece engaging elements on the tong arms, a second crossbar, and means operatively connecting said second crossbar with said tong arms to cause the latter to be swung relative to

- each other in certain directions when the tongs is supported by the second crossbar and in the opposite directions when the tongs is supported by the first crossbar, said means comprising a pair of upturned actuating arms integral with said tong arms and extending above said first crossbar in planes inclined toward each other, and blocks carried by said actuating arms, said blocks having horizontally aligned bores loosely receiving said second crossbar, said bores being oversize in relation to the size of the second crossbar to permit limited sliding movements of the blocks on the second crossbar without binding of these parts.
- 5 2. A tongs comprising a crossbar, a pair of tong arms pivotally suspended from the crossbar, in-turned tong fingers on said tong arms, upturned actuating arms rigid with said tong arms and extending above said crossbar in directions inclined toward each other, blocks rigid with said upturned actuating arms, said blocks having horizontally aligned bores, a second crossbar of smaller diameter than said bores, said second crossbar extending through and being loosely supported by the bores of said blocks, whereby said blocks may move longitudinally of the crossbar to limited extents on relative vertical movements between said two crossbars, stop elements on said second crossbar to limit the outward movements of said blocks on the second crossbar, and an apertured attaching lug fast to and up-standing from the middle portion of said first crossbar, said attaching lug and the adjacent portion of said second crossbar being adapted to be engaged alternatively by a hook of a hoist or the like.
